UNITED STATES PATENT OFFICE.

JOHN SWEENEY, OF SALISBURY, CONNECTICUT.

DEVICE FOR CUTTING, CARVING, AND FLUTING BONE, HORN, &c.

SPECIFICATION forming part of Letters Patent No. 354,876, dated December 21, 1886.

Application filed August 13, 1886. Serial No. 210,769. (No model.)

To all whom it may concern:

Be it known that I, JOHN SWEENEY, a citizen of the United States, residing at Salisbury, in the county of Litchfield and State of Connecticut, have invented certain new and useful Improvements in Devices for Cutting, Carving, and Fluting Bone, as described; and I do declare the following to be a full, clear, and exact description of the invention, such as will enable others skilled in the art to which it app pertains to make and use the same, reference being had to the accompanying drawings, and to the letters and figures of reference marked thereon, which form a part of this specification.

This invention pertains to certain new and useful improvements in devices for cutting, carving, and fluting bone, horn, and like substance in imitation of stag-horn; and it consists in the construction, combination, and arrangement of the parts in the accomplishment of this result, substantially as hereinafter fully set forth, and particularly pointed out in the claim.

In the accompanying drawings, Figures 1 and 2 are side elevations of my invention. Fig. 3 is a cross-sectional view on the line xx ; Fig. 1; and Fig. 4 is a modification with the ends of the sections broken away.

The principal feature of my invention consists in combining in one device or tool a series of sectional cutters, with different-shaped ends on each cutter, each of said cutters having a series of different-beveled cutting-points in the end thereof, said device or tool being moved over a waved guide-bar inserted between any two of the sectional cutters for the purpose of forming a regular or irregular motion, as may be desired.

In carrying out my invention, I employ an approximately oblong-shaped device or tool, A, having tapered ends, whereon are fitted correspondingly-shaped handles a , and this device or tool is formed with four or more downwardly-projecting cutting-sections, a' , between which sections are formed recesses or spaces a^2 , provided on their inner and side edges with beveled ends, the purpose of which will appear farther on.

Each cutting-section a' has different-shaped lower ends, wherein are formed dissimilar

points or edges b , beveled from their lower front edge forwardly, said points or edges being designed to act upon the rounded surface of the knife-scale in the cutting, carving, or fluting of the bone or horn in imitation of stag-horn.

B is an oblong narrow guide-bar, the upper edge of which is provided throughout its length with curved or waved portions b' , irregular in their formation, and this guide-bar is designed to be placed within any one of the recesses or spaces a^2 , so as to cause the device or tool, together with its cutting-sections, to have an inordinate or uneven motion when being drawn over the curved or waved portion of said bar.

In operation the knife-scales are shaped and figured prior to being cut, carved, or fluted, and the knife-scale, bone or horn, or other material to be acted upon, is placed parallel with the curved or waved guide-bar, after which the device or tool—the handles of which are held by both hands of the operator—is drawn over the guide-bar; and the cutting, carving, or fluting is effected by raising and advancing one of the handled ends of my device or tool and depressing and receding the other corresponding handled end while in motion passing over the said guide-bar, and thus acting upon the knife-scale.

By providing the device or tool with the series of recesses or spaces a^2 , for passing the same over the guide-bar, I am enabled to use a greater number and variety of cutting-sections, and the cutting, carving, or fluting can thus be performed in less time and with greater facility than when a separate device or tool is employed for each cutting-section.

After the operation of cutting, carving, or fluting of the knife-scale, bone or horn, &c., has been accomplished, I subject the same to the action of a chemical compound for coloring, which may be varied accordingly as may be desired.

In Fig. 4 I have shown a modified form of my invention, which consists in providing means for the application of additional force or pressure to the sectional cutters, and the same is accomplished by securing the handles at each end of the device or tool in an upright inclined position; also, in providing adjustable

handles *d*. Said handles have a small slot or recess formed in their central or body portion for passing the same on the device or tool over each sectional cutter, and the same are thus securely held in position by means of small thumb-screws *d'*, passed through one side of the ends of said handles, and impinging against the device or tool. By means of this construction, other than hand-power may be employed, and several knife-scales may be acted upon at the same time.

Having thus fully described my invention, what I claim, and desire to secure by Letters Patent, is—

In a device for cutting, carving, and fluting, 15 the combination of the tool having a series of cutting-sections of dissimilar ends, the recesses formed between said sections, and the guide-bar having a curved or waved portion, said recesses being adapted to receive the 20 guide-bar, substantially as shown and described.

In testimony whereof I affix my signature in presence of two witnesses.

JOHN SWEENEY.
